UNITED STATES PATENT OFFICE.

FRANK HOWARD, OF POTTER, KENTUCKY.

VAPORIZING DEVICE.

Application filed March 9, 1920. Serial No. 364,497.

To all whom it may concern:

Be it known that I, FRANK HOWARD, a citizen of the United States, residing at Potter, in the county of Lawrence and State of Kentucky, have invented new and useful Improvements in Vaporizing Devices, of which the following is a specification.

This invention resides in the provision of a crude oil vaporizer for use in conjunction with a combustion engine and embodies means for initially heating and vaporizing the fuel to start the motor subsequent to which the fuel is conveyed from its source to a heating chamber surrounding the exhaust manifold, wherein it is properly heated and vaporized and then introduced through a valved communication into the intake manifold.

More specifically stated, the means above referred to for initially heating the fuel for the starting of the motor, is in the form of a burner having flues and oil chambers surrounding the flues, the chambers being of such cross sectional configuration to provide maximum heating surfaces, so that the fuel entering the chambers will be properly heated and vaporized in quick order.

In carrying out the invention, I provide means for supplying the fuel tank with air under pressure from the motor, the means including a safety valve so that the pressure in the tank is maintained at a more or less constant degree.

The nature and advantages of the invention will be better understood when the following detail description is taken in connection with the accompanying drawings, the invention residing in the construction, combination and arrangement of parts as claimed.

In the drawings forming part of this application like numerals of reference indicate similar parts in the several views and wherein:—

45 Figure 1 is a view in side elevation showing the invention coupled with a motor.

Figure 2 is a sectional view taken on the line 2—2 of Figure 1 looking in the direction of the arrow.

50 Figure 3 is a sectional view taken on the line 3—3 of Figure 1.

Figure 4 is a view similar to Figure 2 of a modified construction.

55 Figure 5 is a view similar to Figure 3 of a modified form of the invention.

Referring to the drawings in detail, A

indicates generally a combustion engine, wherein 10 indicates the intake manifold, and 11 the exhaust manifold. 12 indicates the dash board of a motor vehicle and 13 the operator's seat.

The vaporizer forming the subject matter of my invention comprises a heating chamber 14 which surrounds the exhaust manifold 11, this chamber having communication with the intake manifold 10 through the medium of a short pipe 15. Communication between the heating chamber 14 and the pipe 15 is controlled by means of a valve 16 which may be controlled by the operator from the seat 13 in any suitable manner. The heating chamber 14 also communicates with the supply tank 17 through the instrumentality of a branch supply pipe 18 leading from the main supply pipe 19. The latter is equipped with a valve 20 to control the communication between the same and the fuel tank 17. Arranged within the branch 18 is a valve 21 which controls the amount of fuel admitted into the heating chamber 14. The branch 18 is also provided with a U-shaped pipe 22 terminally connected with said branch 18 at opposite sides of the valve 21, while the U-shaped pipe is equipped with a check valve 23. This construction obviously provides for the return of fuel from the chamber 14 into the branch 18 and supply pipe 19 incident to expansion in the heating chamber 14.

For the purpose of initially heating and vaporizing the fuel to start the motor, I provide a heating device indicated generally at B and included in the connection between the fuel supply pipe 17 and the intake manifold 10. The heating device is in the nature of a burner having a wick chamber 24 into which the wick 25 projects, and spaced concentrically disposed heating chambers 27 and 28 respectively, more clearly illustrated in Figure 2. The wick chamber 24 is supplied with fuel from the tank 17 through the supply pipe 19 which has communication with a float chamber 29. This chamber is in communication with the wick chamber 24 and contains a float valve 30 which controls the level of the fuel within the wick chamber 24. The fuel from the tank 17 is conveyed to the heating chambers 27 and 28 respectively of the burner through a branch pipe 31 leading from the main supply pipe 19. The chambers 27 and 28 are brought together in a dome at the top, this dome be-

ing indicated at 32, and from which leads the discharge pipe 33 for conveying the fuel from the dome 32 into the intake manifold 10. This communication is controlled by 5 means of a valve 34. As shown in Figure 2, each of the heating chambers is defined by the space between the inner and outer shells 35 and 36 respectively, the inner shell 35 forming part of the heating chamber 27 10 is used as a flue 37, while the space between the outer shell 36 and the inner shell 35' of the chamber 28 defines another flue indicated at 38. To maximize the heating surface of the respective heating chambers the 15 inner wall 35' of the chamber 28 and the outer wall 36' of the chamber 27 are corrugated as indicated at 39. The corrugations of the two mentioned shells of the respective burners extending toward each 20 other and are disposed in staggered relation within the flue 38 as clearly illustrated in Figure 2.

Arranged adjacent the seat 13 is a hand actuated pump 40 for supplying the tank 25 17 with air through the pipes 41 and 42. The pipe 42 communicates with the tank 17 at one end, and with the space between the double diaphragm 43. The double dia- 30 phragms form part of a regulator interposed between one cylinder of the motor A and the pipe 42, so that air may be conveyed from the motor through the pipe 42 to the tank 17, in counter-distinction to the use of the hand pump 44 for this purpose. The 35 regulator maintains the air pressure within the fuel tank at a constant degree. Associated with the cylinder mentioned is a coupling 45 which establishes a communication between the cylinder of the motor and 40 an air line 46 which leads from the coupling 45 to the space between the double diaphragm 43. The air line 46 includes a check valve 47 and an air strainer 48. In 45 practice, the air is forced from the cylinder of the motor to the air line 46 into the space between the double diaphragm 43, the latter being provided to prevent interruptions in the flow of air from the motor to the tank 17. Obviously the air passes 50 from the space between the double dia- phragm which as above stated forms part of a regulator, through the pipe 42 to the tank 17, maintaining the pressure in the tank at a constant degree. Mounted upon the dash 55 board 12 is a gauge 49 communicating with the pipe 42 by means of an extension 50. The gauge is equipped with a safety valve 51 of any suitable construction and by use of 60 which the pressure in the tank 17 is maintained at a more or less constant degree.

In practice, the burner B is first lighted and the valve 52 opened to allow the fuel from the tank 17 to pass through the pipe 19 into the heating chambers 27 and 28 re- 65 spectively of the burner and to also pass

through the chamber 29 into the wick chamber 24. The fuel in the chambers 27 and 28 is properly heated and vaporized therein and conveyed through the pipe 33 into the intake manifold 10. After the motor has 70 been started the burner B is extinguished and the valve 52 closed. The fuel from the tank 17 is then conveyed to the supply pipe 19 and the branch pipe 18 into the heating chamber 14 which surrounds the exhaust 75 manifold 11. Obviously the fuel admitted to the heating chamber 14, is heated and vaporized from the heat of the exhaust, and is conveyed from the chamber 14 to the in- 80 take manifold through the valve connections 15 and 16. The valve 21 may be fully opened to admit a predetermined quantity of fuel from the tank 17 into the heating chamber 14 and then closed, or it may be opened to any desired degree depending upon the particular quantity of fuel to be admitted to the heating chamber 14. In 85 other words, the valve 21 may be maintained open at all times, while the machine is in use, and properly adjusted to regulate the quantity of fuel admitted to the chamber 14. The return of fuel from the chamber 14 incident to the expansion of the chamber or for any other reason, is allowed to pass 90 through the pipe 22 and check valve 23 into the main supply pipe 19. A similar construction is provided for the return of fuel from the heating chambers 27 and 28. In 95 this connection it will be noted that the supply pipe 19 in advance of its connection with the branch pipe 18 is provided with a U-shaped pipe 54 terminally connected with the pipe 19 at opposite sides of the valve 52, the U-shaped pipe being equipped with a check valve 55. Now, as the motor continues to operate, the air is forced through 100 the air line 46, the check valve 47 and air strainer 48 into the space between the double diaphragms 43, from where it is conveyed 105 through the pipe 42 into the tank 17. As above stated, a safety valve is included in this connection so as to maintain the pressure within the tank at a more or less constant degree.

In Figure 4, I have disclosed a modified form of an exhaust manifold. In this instance, the exhaust manifold is indicated at 110 56 and is corrugated or fluted, the corrugations 57 being longitudinally disposed and projecting within the manifold as shown. The manifold is surrounded by a heating chamber 58 and by reason of the construction illustrated it is obvious that a maximum heating surface for the fuel is provided. In other words, the fuel is not only heated in the space between the manifold and the heating chamber the wall of which is indicated at 115 58, but enters the corrugations 57 which by reason of their disposition within the manifold are subjected to the greatest heat intensity of the exhaust.

In Figure 5, I have shown a further modified form of the invention, wherein the exhaust manifold is indicated at 59 and the heating chamber surrounding the same, the 5 wall of which is indicated at 60. Arranged with the exhaust manifold 59 is a coiled pipe 61 having its terminals communicating with the heating chamber as shown at 62. By reason of this construction the fuel is 10 not only heated in the space between the exhaust manifold 59 and the chamber including a wall 60 but a portion of the fuel flows 15 in one end of the coil pipe 61 and out the opposite end thereof, and being returned to the chamber including the wall 60. Consequently the fuel is not only heated to a high temperature but also heated in quick order. For this purpose, it is necessary that the terminals 62 of the coil pipe be submerged or 20 in other words disposed beneath the level of the fuel in the chamber embodying the wall 60.

While it is believed that from the foregoing description, the nature and advantages 25 of the invention will be readily apparent, I desire to have it understood that I do not limit myself to the details herein shown and described, and that such changes may be resorted to when desired as fall within the 30 scope of what is claimed.

Having thus described my invention what I claim as new is:—

1. A vaporizer of the character described comprising a wick chamber, a float chamber arranged to one side of and communicating 35 with the wick chamber, a float valve controlling said communication, spaced concentrically disposed heating chambers, a supply pipe communicating with both the said float chamber and the said heating chambers, a 40 dome common to both of said heating chambers, and an outlet pipe leading from said dome.

2. A vaporizing device of the character described comprising a wick chamber, a float 45 chamber arranged to one side of and communicating with the wick chamber, a plurality of spaced concentrically disposed shells defining a plurality of heating chambers, a supply pipe communicating with the 50 wick chamber, and with said heating chambers, the said shells being radially corrugated in a longitudinal direction, with the corrugations of the respective shells extending toward each other and disposed in staggered relation, a dome common to said 55 heating chambers, and an outlet pipe leading from said dome.

In testimony whereof I affix my signature.
FRANK HOWARD.
